Specification for Design.

Patented July 13, 1920.

Application filed April 1, 1920. Serial No. 370,574. Term of patent 3½ years.

To all whom it may concern:

Be it known that I, FRANCOIS RICHARD, a citizen of the French Republic, residing at 7800 Finney Ave., in the city of Cleveland, county of Cuyahoga, and State of Ohio, have invented a new, original, and ornamental Design for an Automobile-Body, of which the following is a specification, reference being had to the accompanying drawing, forming part thereof.

The drawing is a side elevation of an automobile.

I claim:

The ornamental design for an automobile body as shown.

FRANCOIS RICHARD.
